UNITED STATES PATENT OFFICE.

HARRY WALLACE THOMAS, OF INDIANA, PENNSYLVANIA.

DESIGN FOR A BOWL OR SIMILAR ARTICLE.

Application filed March 21, 1924. Serial No. 9,017. Term of patent 7 years.

To all whom it may concern:

Be it known that I, HARRY WALLACE THOMAS, a citizen of the United States of America, and a resident of Indiana, in the county of Indiana and State of Pennsylvania, have invented a new, original, and ornamental Design for a Bowl or Similar Article, of which the following is a specification, reference being had to the accompanying drawing, forming a part thereof and in which—

I claim:

The ornamental design for a bowl or similar article, as shown.

HARRY WALLACE THOMAS,
